UNITED STATES PATENT OFFICE.

BAYLUS CADE, OF SHELBY, NORTH CAROLINA, ASSIGNOR TO CADE MANUFACTURING COMPANY, OF SHELBY, NORTH CAROLINA, A CORPORATION OF NORTH CAROLINA.

LINE COMPOSING AND CASTING MACHINE.

1,257,185.

Specification of Letters Patent. Patented Feb. 19, 1918.

Application filed June 10, 1915. Serial No. 33,382.

To all whom it may concern:

Be it known that I, BAYLUS CADE, a citizen of the United States, residing at Shelby, in the county of Cleveland and State of North Carolina, have invented new and useful Improvements in Line Composing and Casting Machines, of which the following is a specification.

My present invention relates to improvements in line composing and casting machines of the class wherein matrices are selected and composed in a line and a type slug is cast therefrom, and the primary objects of the invention are to provide a generally improved and simplified machine of this character which is capable of being manufactured and maintained at relatively small cost and may be operated with rapidity and facility, the matrices being mounted on movable sectors and selected by manipulation of a keyboard, the sectors then carrying the selected matrices to the assembling point whereupon the selected matrices are gathered together and alined before a mold, the casting mechanism then operating to cast a slug bearing a type face made directly from the matrices, the casting mechanism and the matrices being thereupon restored to normal position preparatory to the next casting operation.

Another object of the invention is to provide improved keyboard and matrix selecting mechanism whereby the selection of the matrices for the different lines is accomplished with facility, means being provided for measuring the length of each line of matrices according to the varying thicknesses of the different matrices selected whereby each composed line will be of the proper length and the characters will be more correctly spaced than heretofore, the keyboard being automatically locked when a full line has been selected and automatically unlocked only when the keyboard mechanism is set for the selection of another line of matrices. A subsidiary object is to provide an improved carriage for the keyboard mechanism which insures certainty in operation and which embodies means whereby provision may be made for the subsequent introduction of additional spacers in the line and also means whereby the carriage may be rendered inoperative preparatory to

the restoring of the carriage to initial position.

Another object of the invention is to provide improved means for rotating the sectors to bring the selected matrices to the assembling and casting position and for restoring the sectors to initial or matrix selecting position, and also improved means for shifting the sectors whereby the selected matrices are extended preparatory to the casting operation and returned to their normal positions on the sectors subsequent thereto.

To these and other ends, the invention consists in certain improvements, and combinations and arrangements of parts, all as will be hereinafter more fully described, the novel features being pointed out particularly in the claims at the end of the specification.

In the accompanying drawings:

Figure 1 is a side elevation of a line composing and casting machine constructed in accordance with the present invention;

Fig. 2 is a top plan view, partly in section, of the machine as shown in Fig. 1;

Fig. 3 represents a transverse vertical section through the machine taken through the axis of the matrix sectors;

Fig. 4 is a side elevation, partly in section, of the central portion of the left-hand side of the machine;

Fig. 5 is a diagrammatic view, in section, illustrating the manner of selecting the matrices from the keyboard and controlling the movement of the sectors to bring the selected matrices to the assembling and casting position;

Fig. 6 is a detail view of the left-hand side of the keyboard showing the device for locking the keyboard to prevent subsequent manipulation thereof after a full line of matrices has been selected;

- 50 Fig. 29 shows the selecting carriage as viewed from the rear;
- Fig. 30 is a perspective view of the selecting carriage;
- Fig. 31 is a top plan view of the carriage;
- 55 Fig. 32 represents a horizontal section of the carriage on the line 32—32, Fig. 28;
- Fig. 33 is a perspective view of the operating means for the keyboard lock;
- 60 Fig. 34 is a perspective view of the selecting carriage and its rail;
- Fig. 35 is a detail perspective view of the keys on the selecting carriage;
- 65 Fig. 36 is a sectional view of the matrix sectors taken in the plane of their axis;

Fig. 37 is a detail sectional view illustrating the friction plungers for the sectors;

Fig. 38 is a side elevation of the matrix-carrying mechanism showing in section one of the friction plungers;

Fig. 39 is a perspective view of one of the matrices;

Fig. 40 is a perspective view of one of the wedge or expansible spacers;

Fig. 41 represents a section taken longitudinally of the expansible wedge of the spacer;

Fig. 42 represents a section through the spacer and taken longitudinally of its supporting stem;

Fig. 43 is a top plan view of the mechanism for revolving the matrix sectors to carry the selected matrices to and from the assembling and casting position;

Figs. 44 and 45 are detail views of parts of the mechanism shown in Fig. 43;

Fig. 46 is a detail view showing the means at one side of the machine for operating and controlling certain parts which may be hereinafter described;

Fig. 47 is a detail view showing the means for reciprocating the matrix sectors;

Fig. 48 is a perspective view of the casting mechanism, the matrix gathering, clamping and alining devices;

Fig. 49 is a detail view of the mold and its co-operating parts and also the operating means for the casting mechanism;

Fig. 50 is a detail view of the lock which controls the operation of the metal pot;

Fig. 51 represents a longitudinal section through the casting mechanism;

Fig. 52 is a top plan view of the same;

Fig. 53 is a detail view showing the mechanism for operating the alining bars and vise jaws and the mold sections as well as the means for operating the slug ejector and related parts;

Fig. 54 is a detail view of the justifying slide;

Fig. 55 is a perspective view of the same;

Fig. 56 is a detail view of the cam which controls the reciprocating movements of the matrix sectors;

Fig. 57 is a detail perspective view of the slug trimming mechanism;

Fig. 58 is a perspective view of a multiple letter matrix.

Similar parts are designated by the same reference characters in the several views.

The machine in the construction shown comprises a suitable base 1 and a pair of main frames 2 and 3 which are mounted thereon and serve respectively to support the matrix selecting mechanism and the casting mechanism. According to the present invention the matrices are carried by a plurality of matrix sectors 4, the matrices being arranged on the peripheries of the sectors and the sectors having hubs which

frictionally fit rings 5. The rings 5 are mounted to turn with a drum 6, they being keyed thereto by the key 7. In the operation of the machine the drum 6 is rotated in one direction to carry the selected matrices to the assembling and casting position and it is rotated in a reverse direction after the casting operation to return the sectors and the matrices thereon to their normal or initial position. In order to insure correct rotation of the sectors in each direction, a spring plunger 8 is provided for each sector, each plunger operating in a casing 9 which is fixed to and is arranged within the drum 6 and contains a spring 10 which acts to force the plunger outwardly through the drum and against the inner periphery of the hub of the respective sector. Preferably, the inner circumference of the hub of each sector is formed with a pair of recesses 11 and 12, these recesses being connected by a beveled surface 13. Referring to Fig. 38, when the drum is revolving in an anti-clockwise direction to carry the selected matrices to the assembling and casting position, the plungers 8 will move out of the recesses 11, riding up the beveled surfaces 13 and will enter the more abrupt recess 12, it remaining in engagement with this latter recess and insuring rotation of the sector until the selected matrix reaches the assembling and casting position, whereupon the sector will be stopped by mechanism to be hereinafter described. When the drum 6 is rotated in a reverse direction after the casting has occurred, the spring plunger 8 will leave the recess 12 and will enter the recess 11, it riding upon the beveled side thereof thereby insuring return of the corresponding sector to normal or initial position. The drum 6 is supported on a shaft 14 and the latter is journaled in bearings 15, the latter being formed on the side walls of a trough 16 which is mounted on rollers 17 which latter travel on horizontal tracks 18. A sprocket wheel 19 is fixed to the shaft 14 at each side of the drum, a sprocket chain 20 cooperates with each sprocket wheel and said sprocket chains coöperate with a pair of sprocket wheels 21, the latter being fixed on a shaft 22 which shaft is journaled in relatively fixed bearings 23 on the base of the machine. In order to retain the sprocket chains in proper coöperative relation with the sprocket wheels 21 during the reciprocating movements of the trough 16 on the tracks 18, a pair of guides or idlers 24 are provided to engage the outer sides of the stretches of the sprocket chain 20 and to take up slack therein during the middle portion of the travel of the trough. A bevel gear 25 is fixed on the shaft 22 and this bevel gear coöperates with a bevel pinion 26, the latter being fixed to a shaft 27 which is journaled in a frame 28 and has a screw 29 formed thereon and a nut 30 which co-operates therewith. The opposite end of the shaft 27 has a bevel gear 31 fixed thereon which meshes with a pair of reversely arranged bevel gears 32 and 33, jaw clutches 34 and 35 being fixed to the inner or adjacent ends of the bevel gears 32 and 33 respectively and the double jaw clutch 36 being mounted shiftably between the jaw clutches 34 and 35 and arranged to coöperate with them alternately. The bevel gears 32 and 33 are loosely mounted on the main drive shaft 37 while the double jaw clutch 36 is keyed or splined on the main drive shaft. When the clutch 36 is in neutral position, that is to say, out of engagement with both clutch members 34 and 35, the gears 31, 32 and 33 will be idle. When however, the clutch 36 is engaged alternately with the clutch members 34 and 35, the drum 85 and the sectors frictionally mounted thereon will be rotated alternately in reverse directions. The screw 29 is employed to limit the extent of rotation of the drum in each direction, the arm 38 on the nut 30 being arranged between a pair of stops 39 and 40 whereby the arm 38 will engage these stops alternately after the shaft 27 has revolved to a predetermined extent in each direction, it being understood that the nut 30 travels in reverse directions in accordance with the direction of rotation of the shaft 27. The stops 39 and 40 are fixed at proper positions on a rod 41, the latter being supported at one end by an arm 42 which is pivoted at 43, and the opposite end of the rod 41 is connected to one arm 44 of a bell-crank, said bell-crank being pivoted to the frame 28 at 45 and having an arm 46 which is operatively connected to the clutch 36 and serves to shift it alternately into engagement with the clutch members 34 and 35. Obviously, endwise movement of the rod 41 in each direction due to the traveling movement of the arm 38 will cause the clutch 36 to be disengaged from either of the clutch members 34 and 35, thereby returning the clutch 36 to neutral position and interrupting the rotation of the drum supporting the sectors. Engagement of the clutch 36 alternately with the clutch members 34 and 35 is effected by a rod 47 which is connected to the bell-crank at one end and its opposite end is supported by an arm 48 pivoted at 49 to a bracket 50, the arm 48 being provided with a roller 51 which coöperates with an actuating cam 52, the latter being mounted on a shaft 53.

The matrices, as previously stated, are arranged peripherally of the sectors. In the construction shown, each sector has a number of radially extending tubes 54 which are fixed at their inner ends to the hub of the sector and their outer ends are contracted, as at 55, and are connected by semi-circular 130

rings 56. Each matrix comprises a body 57 having a matrix character 58 in the outer end thereof and being attached at its inner end to a stem 59, the stem of each matrix 5 slidably fitting into one of the tubes of the sector, and in order to prevent displacement or dropping of any of the matrices from the sector, especially when such matrices are rotated to the under side of the sector, the 10 stem is preferably expanded laterally to form a spring 60 which will frictionally fit the neck or reduced portion 55 of the tube when the matrix is in its normal retracted position, as shown in Fig. 37. The body of 15 the matrix is also formed with an aperture 61 to receive the alining bars to be herein-after described, the outer ends of this aperture having beveled alining faces 62. Each sector is also provided with an expansible 20 spacer which spacer serves to justify the line of matrices. In the construction shown in Figs. 40, 41 and 42, each spacer comprises a body 63 formed with an aperture 64 having a beveled outer end 65 to receive and co-operate with the alining bars, and the spacer is provided with a pair of stems 66 which 25 slidably fit a pair of tubes on the respective sector. The outer end of the body 63 has a dove-tail groove 67 which slidably receives a 30 wedge 68. Pressure upon the larger end of the wedge 68 will slide the wedge in the body 63, thereby increasing the width of the spacer and expanding the line of matrices to the full length.

35 Preferably, the matrices are arranged on approximately one-half the circumference of each sector, as appears from Fig. 38. The other half of each sector is utilized as a means for stopping and positioning the sector when the selected matrix has reached the 40 assembling and casting position. In the construction shown, the stopping and positioning means embodies a disk 69 which is formed with a series of teeth 70 which correspond in number and relative position on the disk to the respective matrices on the sector. These teeth are spaced at progressively increasing distances from the center or axis of 45 rotation of the sector, that is to say, their center is eccentric to the center of rotation of the sector. A series of stop bars 71 are provided which correspond in number to the 50 number of sectors employed, these stop bars being arranged in a row and in the planes of the respective toothed disks on the sectors. These stop bars are slidable longitudinally 55 and toward and from the respective toothed disks. By setting the stop bars at different distances from the center of rotation of the 60 sectors, the sectors will be stopped at different points, it being obvious that the eccentrically located teeth 70 will approach the adjacent ends of the stop bars as the rotation of the sectors progresses toward the assembling position. In order to insure a rela-

tively firm engagement between the teeth 70 and the respective stop bar, a dog 72 is provided for each stop bar, the dog being pivoted thereto on the pivot pin 73 and provided with a spring 74 which operates to 70 normally hold the dog in an inactive position, as appears in Fig. 13. When, however, the tooth 70 (which is intended to be engaged by the dog 72 according to the position in which the stop bar 71 is set) engages 75 the free end of the dog 72, the continued rotation of the sector will swing the dog 72 upwardly against the action of the spring 74 until the inner end 75 of the dog abuts against a shoulder 76 of the stop bar, the dog 80 then assuming the position shown in Fig. 14 and providing a solid stop to arrest rotation of the sector. Owing to the location of the pivot 73, the movement of the dog 72 into arresting position after being engaged by 85 the tooth on the sector causes the dog to engage a greater portion of the tooth, as will appear from Fig. 14, thereby preventing escape of the tooth past the dog and reducing wear or breakage of the teeth to a minimum. Each stop bar 71 is preferably held frictionally in its selected position by a friction spring 77 and is provided with an upturned lug 78 with which a resetting rail 79 is adapted to co-operate to restore the stop 90 bars to initial position. Rotation of the sectors in a reverse direction after the cast has been made to restore them to normal position is arrested by an arm 79^a which is fixed to and projects from each sector and is 100 adapted to come to rest on a stop rail 80 which latter may be composed of or faced with a shock absorbing material as felt adapted to cushion the sectors when they come to rest.

105 The keyboard comprises a set of key levers 81 corresponding in number to the number of sets of matrices on each sector. In the present instance, each sector is adapted to carry three sets of matrices, one set 110 of matrices pertaining to lower case characters, another set to upper case characters, and the third set to figures or special characters. The sets of matrices are arranged in alternating relation on the sector with 115 the matrices of each set following in regular order, and hence the matrices of any set will be controlled in their selection by the appropriate one of three adjacent teeth 70. In the present instance, one set of key 120 levers 81 serves to control the selection of the three sets of matrices, as will hereinafter appear. Each key lever is fulcrumed or pivoted at 82 in the keyboard frame and is provided at its forward end with an appropriate finger key 83 bearing thereon the characters corresponding to the matrices which the respective key controls. In rear of the key levers are arranged a transversely extending series of stops 84 which corre- 125 130

spond in number to the number of key levers and are connected to the key levers by the rods or links 85 whereby depression of the finger key on any key lever will cause rising of the stop connected to it. Each stop 84 is mounted to rise and fall bodily. To effect this result, the opposite ends of each stop are connected to a pair of links 86 and said links are pivotally connected at 87 to 5 a sliding frame 88, the latter being movable in a direction transversely of the stops 84 whereby it may occupy three positions corresponding to the three sets of matrices on the sector. Tension springs 89 serve to 10 turn the stops 84 and the key levers 81 to normal position after each operation thereof. Shifting of the sliding frame 88 to enable matrices belonging to different sets to be selected is effected by either of two shifting key levers 90 and 91, the key lever 90 in the present instance serving to shift the stops for the selection of upper case or capital letter matrices and the shifting key lever 91 serving to shift the stop for the selection 15 of matrices of the set bearing figures or special characters, the shifting of the stops 84 by the lever 91 being greater in extent than the shifting movement effected by the lever 90. To this end, the lever 91 20 has its hub 92 fixed directly on a rock shaft 93, the latter being connected by an arm 94 thereon and a link 95 to the sliding frame 88 whereby the shifting movement of the stops will correspond to the extent of movement of the lever 91. The hub 96 of the lever 90 is loosely mounted on the rock shaft 93 and has an arm 97 projecting laterally therefrom and resting in a notch 98 in the hub 92, and a lug 99 projects from the hub 25 40 45 50 55 60

ing bar 104 is provided, this bar being slideable endwise above the stops 84 and is confined in guides or bearings 105. The under side of this locking bar is provided with teeth or projections 106 which correspond in number and spacing to the stops 84, and when the locking bar occupies a position with the projections 106 above the stops, the latter will be locked or prevented from rising, whereas when the locking bar 70 75 80 85 90 95 100 105 110 115 120 125 130 rises, the latter are then free to rise. The shifting of the locking bar to lock the stops 84 is accomplished automatically. In the present instance, it is connected to an arm 107 of a bell-crank which is pivoted at 108 to a rail 109, the other arm 110 of the bell-crank being connected by a link 111 to a lever 112, the latter being pivoted on a shaft 113 which latter is journaled in the rail 109, and the lever 112 is connected by a link 114 to the rear end of a lever 115, the latter being pivoted at 116 to a part of the stationary keyboard frame 90 and its forward end is formed with a lug or projection 117 which co-operates with a disk or wheel 118. The latter is fixed to a shaft 119 and is formed with diametrically spaced notches 120 adapted to receive the lug 117 95 on the lock-actuating lever 115. Upon the actuation of each key lever, the disk or wheel 118 is rotated a distance corresponding to the thickness of the particular matrix selected, and when the aggregate thickness 100 of the selected matrices corresponds to the length of the line, one of the notches 120 in the disk will reach and receive the lug or projection 117, thereby causing the lever 115 to rock, and operating through the connections just described, to shift the locking bar 104 to bring the teeth or projections 106 thereon directly above the stops 84, thereby preventing rising of any of the stops and effectually locking the keyboard from further manipulation. During the selection of the matrices to compose a line, however, the projection 117 on the lever 115 will ride upon the unnotched periphery of the disk 118 and the lock will be thereby held in 110 inoperative condition. Rotation of the disk 118 is effected by a ratchet wheel 121 which is fixed on the shaft 119 and with which co-operates a multiple pawl device 122, the latter embodying arms 123 which are rotatable concentrically with the shaft 119 and are connected by a cross-rail 124. A set of three links 125, 126 and 127 co-operate with the cross-rail 124, they being slotted to engage the cross-rail 124 whereby reciprocation of the rail 124 and the pawl device of which it is a part may take place without movement of the other links. These links are pivotally connected by arms 128, 129 and 130 to a set of rock shafts 131, 132 and 130

The present invention provides means for automatically locking the keyboard from further operation when a number of matrices sufficient to fill the line have been selected. In the construction shown, a lock-

133 respectively, and these rock shafts are journaled at their ends in the side frames 134 and 135 of the keyboard. The shafts 131, 132 and 133 are also shiftable endwise 5 or axially according to whether the selected matrix belongs to the lower case, the upper case, or the series bearing figures or special characters. A pair of abutments 136 and 137 are fitted on the shafts 131, 132 and 133 10 at points adjacent to their ends, and springs 138, 139 and 140 are interposed between the abutment 136 and the side frame 134 and tend to normally hold the shafts toward the right-hand position, as shown in Fig. 18. 15 The shafts 131, 132 and 133 are located between the finger keys, and each rock shaft is provided with a matrix-gaging device corresponding to a key lever. One of these matrix-gaging devices is shown in detail in 20 Fig. 9, it consisting of a head 141 which has an arm 142 whereby it is rigidly connected to its respective rock shaft, and the head is formed with three shoulders, the shoulder 143 being engaged by the key lever in the 25 selection of matrices belonging to the lower case, the shoulder 144 being engaged by the key lever in the selection of matrices belonging to the upper case, and the shoulder 145 being engaged by the key lever in the selection 30 of matrices bearing figures or special characters. The particular shoulder engaged by the key lever depends upon the longitudinal position of the rock shaft, it being understood that the gaging devices 35 are shifted laterally of the key levers with the lateral shifting of the rock shafts. This lateral shifting of the rock shafts to bring the proper gaging shoulder into position to be engaged by the key lever is effected 40 automatically and in unison with the shifting of the slide 88 to position the stops 84. In the construction shown, the shifting of the shafts 131, 132 and 133 is effected by a lever 146 which is pivoted at 147 to the 45 stationary keyboard frame and is connected at its upper end to the abutment 137. The lower end of the lever 146 has an elongated slot 148 in which a pin 149 operates, the pin 149 being fixed to a lever 150 and the latter 50 is fixed to a rock shaft 151, said rock shaft having an arm 152 fixed thereto which arm is operatively connected by a link 153 to the sliding frame 88. Consequently, sliding of the frame 88 forwardly to bring the stops 55 84 either into the first position for the selection of upper case characters or into the second position for the selection of matrices bearing figures will cause corresponding endwise movement of the shafts 131, 132 60 and 133 whereby the appropriate shoulders on the gaging devices are brought beneath the key levers and depression of any key lever will cause rotation of the respective rock shaft to an extent corresponding to the 65 thickness of the selected matrix. The ex-

tent of rotation of the rock shaft determines the degree of rotation imparted to the disk 118. Preferably, a signal is provided to warn the operator when a line is nearing completion. In the construction shown, a double cam 154 is fixed on the shaft 119 and cooperates with one end of a lever 155, the latter being pressed against the cam by a spring 156 and the opposite end of the lever carries a hammer 157 arranged to strike a bell 158 a suitable distance in advance of the engagement of the projection 117 in the notch 120. The lever 115 is preferably provided with a branch arm 159 and with an extension lever 160, the latter being pivoted 70 on the arm 159 at 161 and provided with a stop 162 adapted to engage against the under side of the arm 159 to normally support the extension lever 160 in operative position. The free end of the extension 75 lever 160 is formed with a notch 163 to receive a tooth 164 on the pawl device which advances the ratchet wheel 121 whereby when the projection 117 rests in one of the notches 120 on the disk 118 the ratchet will 80 be locked from further actuation. In order to prevent overmotion of the ratchet and pawl device, a magnetic brake is provided. This brake embodies a lever 165 which is pivoted at 166 and has a friction surface 85 167 adapted to cooperate with the periphery of the disk or wheel 118. The lever 165 carries an armature 168 arranged to cooperate with an electro-magnet 169. This electro-magnet, the circuit of which is shown 90 diagrammatically in Fig. 26, is energized to apply the brake to the disk 118 each time a lever is depressed, but it is deenergized when the pressure on the key lever is relieved. To this end, a contact 170 is provided for each key lever and is adapted to 95 be engaged thereby when the key lever is depressed, each contact being connected to one side of the circuit of the electro-magnet and the key levers being connected to the 100 other side of such circuit. A switch 171 may be provided at one side of the keyboard to render this electrical device operative and inoperative. 105

The feeding of the expandible spacers into 115 the line is effected under the control of a space key or bar 172 which is connected to a space bar lever 173 and which lever is connected to the appropriate stop 84. One of the rock shafts (the shaft 133 in the present 120 instance) is formed with a crank 174 which lies beneath the space bar lever 173 whereby depression of the space bar to feed a spacer into the line causes the space bar lever 173 to act upon and depress the crank 174, 125 rocking the shaft 133 and thereby advancing the disk 118 a suitable distance corresponding to the thickness of the spacer.

A set of selecting bars 175 is provided, these bars corresponding in number to the 130

stop bars 84 and they are movable transversely of the stop bars 84, the selecting bars in the present instance being shiftable longitudinally and in a direction forwardly and rearwardly of the machine. These selecting bars are slidably mounted in a carriage 176 which carriage is slidable on the frame 2 in a direction forwardly and rearwardly. The upper edge of each selecting bar is formed with a series of teeth 177, and a vertically movable dog 178 is fitted in the carriage 176 and is adapted to coöperate with the toothed upper edge of the respective selecting bar. The lower edge of each selecting bar is formed with rack teeth 179 and a pinion 180 coöperates with such rack teeth. There is a series of pinions 180 corresponding in number and spacing to the selecting bars 175, these pinions being driven frictionally, and the forward shifting of the selecting bars under the influence of the pinions is controlled by the dogs 178. Upon reference to Figs. 21 and 22, it will be understood that the pinions 180 in the present instance are loosely mounted on a continuously revolving shaft 181, the shaft having a longitudinal keyway 182, and a series of friction disks 183 are interposed between the pinions, each of these friction disks having a lug or key 184 which engages in the keyway 182 of the shaft and thereby causes the disks to revolve continuously with the shaft, producing friction upon the adjacent sides of the pinions tending to revolve them, and to project their coöoperating selecting bars 175 forwardly. A suitable number of radially expandable springs 185 are provided to maintain the requisite degree of friction between the friction disks and the faces of the pinions, these springs in the construction shown being composed of disks of resilient material which are convexed and may be slotted radially at the periphery. Supports 186 are provided at intervals along the shaft 181, and these supports serve as spacing means for the intermediate springs. The shaft 181 is driven continuously by a gear 187 which is fixed thereon and a coöperating gear 188, the latter having a sprocket wheel 189 connected thereto over which passes a sprocket chain 190, this sprocket chain coöperating with a sprocket wheel 191 which latter is driven continuously by a chain 192 which coöperates with a sprocket wheel 193, the latter being fixed on the continuously running main drive shaft 37. An idler pulley 194 carried by an arm 195 coöperates with the chain 190 and serves to retain it in proper coöperative relation with the sprocket wheels over which it passes, the arm 195 being acted on by a tension spring 196.

A series of actuating levers 197 is provided for the dogs 178, these levers being pivoted on a common shaft 198 carried by the slide or carriage 176, and a series of

springs 199 is provided which act to hold the levers 197 depressed and the dogs 178 in locking engagement with the selecting bars 175. A releasing rail 200 extends beneath the actuating levers 197 and is capable, when lifted, of simultaneously disengaging all the dogs 178 from the selecting bars. This releasing rail has an arm 201 at each end which is pivotally mounted on the shaft 198 and vertical slides 202 are connected at their upper ends to the arms 201 and reciprocate in vertical guides 203 on the respective sides of the slide or carriage 176. The lower end of each slide 202 has a roller 204 connected thereto by a hinge 205 which permits the roller to occupy a position either in alignment with the slide 202 or a deflected position, as shown by the dotted and full lines respectively in Fig. 20. A spring 206 acts to swing the roller 204 into the aligned position. A track 207 is fitted to reciprocate longitudinally in a groove 208 at each side of the carriage 176, the forward and rear ends of said track having bevels 209 and 210. When the carriage 176 moves from the dotted line position in Fig. 20 to the full line position, the roller 204 will ride up the beveled surface 210 on the track and the releasing rail 200 will thereby lift the levers 197 and simultaneously trip the dogs 178. After the carriage 176 reaches its forward position, as shown by the full lines in Fig. 20, and the track 207 is retracted to withdraw its forward end from beneath the roller 204, the releasing rail 200 drops and the dogs 178 are thereby reengaged with the selecting bars. A lug 211 is provided on each track 207 and is adapted to be engaged by the hook 212 on the bar 213 whereby the track 207 is retracted to permit dropping of the releasing rail 200. A pair of stops 214 and 215 are provided on the frame 2 to coöperate with a stop 216 on the reciprocating carriage 176 whereby the range of movement of this carriage may be properly adjusted and controlled. Reciprocation of the carriage is effected by a pitman 217 which is operatively connected to a crank 218, the latter being connected in turn to an intermittent pinion 219 which has an interrupted gear periphery to coöperate with a correspondingly toothed gear 220 mounted on the shaft 221, (see Fig. 46).

In manipulating the keyboard to select the desired matrices, the stops 84 are elevated and the selection of the matrices is controlled according to the extent of forward movement of the selecting bars 175 as determined by the stops 84. Means is provided for releasing the selecting bars 175 successively and permitting the selecting bars to move forward by the frictionally driven pinions until arrested by the stops 84. In order to cushion the stopping of the selecting bars when they reach the upstand-

ing stop 84, a head 222 is pivoted to the forward end of each selecting bar at 223 and has a downwardly directed point 224 adapted to encounter the upstanding stop 84. A 5 spring 225 acts to retain the head 222 in depressed position. This head 222 also acts as a pawl to permit subsequent rising of the same stop 84 without being obstructed by the previously positioned selecting bar.

10 This action is illustrated in Fig. 11.

The successive tripping of the selecting bars during the selection of the matrices is effected, according to the present invention, by a carriage which acts successively on the 15 actuating levers 197. As shown, a rail 226 is rigidly mounted on the stationary frame of the machine in front of the carriage 176 and above the stop bars 84. This rail has a slide portion 109 and rows of upper and 20 lower ratchet teeth 228 and 229. The carriage 230 is fitted to reciprocate on the slide portion 109 of the rail and has a normal tendency to shift toward the right under the influence of a cord 231 which winds upon a 25 spring-tensioned drum 232. An escapement is provided to coöperate with the ratchet teeth 228 and 229 and thereby permit step-by-step movement of the carriage toward the right. The escapement shown comprises 30 a vertically movable bar 233 which is suitably guided in the carriage 230 and is provided with a cross-member 234 which spans the space above all of the stop bars 84 so that lifting of any one of the stop bars will 35 cause upward movement of the escapement bar 233. This escapement bar is formed with teeth 235 to coöperate with the lower set of ratchet teeth 229 on the stationary rail when the escapement bar is lifted by the 40 rising of one of the stop bars 84. The escapement bar also carries a dog 236 which is pivoted at 237 and has a pin 238 which operates in a slot 239 and thereby limits the movement of the dog about its center 237. 45 A tension spring 240 acts to yieldingly hold the pin 238 at the lower end of the slot 239. When the escapement bar 233 is raised and the teeth 235 are engaged by the lower rack 229, the dog 236 is disengaged from the upper rack 228, and after the dog 236 is 50 disengaged from the upper rack, the spring 240 acts thereon to swing it into a position where it will engage the next adjacent tooth to the right when the escapement bar falls, 55 and falling of the escapement bar disengages the teeth 235 thereon from the lower rack 229 whereupon the carriage feeds one step toward the right. The upper end of the escapement bar is formed with a horizontal 60 forwardly and rearwardly extending guide 241, and a detent 242 is mounted on the guide 241 and is capable of occupying a position either beneath or clear of the free ends of the dog-actuating levers 197.

65 When this detent is beneath the levers 197

and the escapement bar 233 is elevated, it lifts the corresponding lever 197, thereby releasing its dog 178. In some instances, it is desirable to remove the detent 242 from beneath one of the actuating levers 197 in order to avoid operation of one of the levers, thus providing for the subsequent introduction of an additional narrow spacer into the line, and it is also desirable to withdraw the detent 242 from beneath the actuating levers 197 during the return of the carriage to the initial or left-hand position after completion of one line and preparatory to the selection of another line. To accomplish these results, a pin 243 is fixed to the body portion of the detent 242 and extends through a slot 244 arranged longitudinally of the horizontal guide 241, the lower end of this pin engaging the slotted arm 245 of a lever 246, the latter being pivoted on the carriage by the screw 247 whereby rocking of the lever 246 about said screw will cause the detent 242 to reciprocate forwardly and rearwardly on the guide 241 and thereby move it to and from a position beneath the forward end of the actuating levers 197. A spring 248 acts on the lever 246 in a direction to normally retain the detent in operative position beneath the levers 197. Retraction of the detent to permit return of the carriage to the initial or left-hand position is effected by pressure to the left upon a finger key 249 which is carried by a sliding bar 250 on the carriage, this sliding bar being operatively connected to a forwardly projecting arm 251 of the lever 246, the same pressure upon the finger key 249 serving to return the carriage to the left and such return of the carriage being permitted owing to the ratchet shape of the racks 228 and 229 and the coöperating escapement. In order to retract the detent 242 without shifting the carriage, a lever 252 is provided which is pivoted at 253 to a forward extension 254 on the carriage, and the rear end of the lever is operatively connected to a vertically movable slide 255, the upper end of this slide having a beveled cam-shaped surface 256 which is arranged to operate upon a shoulder 257 formed on a bar 258, one end of the latter being operatively connected to a rearwardly extending arm 259 on the lever 246 while the opposite end of this bar is supported by a link 260. The forward end of the lever 252 is provided with a finger key 261 and depression of this finger key will cause lifting of the slide 255 and consequent retraction of the detent, but when the pressure on this finger key is released, the detent will return to initial position under the influence of the spring 248 assisted by the spring 262 which is interposed between the lever 252 and the stationary extension 254. In order to retract the detent and to hold the same in retracted position, a supplemental lever 263 is pivoted 125

- at 264 to the key lever 252, the forward end of this supplemental lever being provided with a finger key 265 and its rear end is arranged to engage beneath a projection 266 formed on the forward end of the stationary extension 254. A tension spring 267 operates on the supplemental lever 263 in a direction to hold the finger key 265 in elevated position. When, however, this finger key 265 is depressed, the rear end of the lever 263 will bear beneath the projection 266, thereby forcing the lever 252 downwardly until the rear end of the lever 263 slips past the projection 266. Release of pressure on the finger key 265 will allow the rear end of the lever 263 to engage the forward side of the projection 266 under the action of the spring 267 and the lever 252 will be thereby held in depressed position with the detent 242 in retracted position. To release the detent and permit it to resume normal position, it is only necessary to depress the key 261, the rear end of the lever 263 being thereby carried beneath or out of engagement with the projection 266.
- Means is provided for returning the locking bar 104 to unlocked position upon the return of the carriage to the left-hand or initial position. In the present instance a lever 268 is attached to the shaft 113 which carries the lever 112, the lever 268 being located at the rear side of the rail 109 and is capable of a limited vertical movement between a pair of stops 269. The lever 268 is normally held yieldably in depressed position by a spring 270, but when the carriage returns to its left-hand or initial position, a roller 271 on the rear side of the carriage engages beneath the lever 268 and lifts the same upwardly, thereby shifting the locking bar 104 into a position where the projections 106 thereon are opposite to the intervals or spaces between the stop bars 84. This same operation disengages the tooth 117 from the notch 120 in the disk 118 and also disengages the lever 160 from the projection 164, the keyboard being thereby unlocked and ready for manipulation to select matrices to compose the next line.
- A bar 272 is provided for the purpose of restoring the selecting bars 175 to normal position. This bar is carried by a pair of arms 273 arranged at opposite sides of the slide or carriage 176 and are pivoted at 274 to arms 275, the latter being pivoted at 276 to the opposite sides of the stationary frame. A tension spring 277 is attached to each arm 275 and operates to move the same forwardly. Each of the tracks 207 is provided with an outwardly projecting arm 278 which operates in a vertical slot 279 of a bar 280, one of these bars being located at each side of the slide 176 and connected to the upper end of an arm 281. The lower end of each arm 281 is pivoted to the main frame at 282 and each of these arms is provided with a roller 283 which cooperates with a cam 284. An arm 285 is provided at each side of the machine, each of these arms being pivoted at its upper end, as at 286, to the bar 280 and at its lower end to the stationary frame, as at 287. A tension spring 288 operates to draw each arm forward and each arm carries a pin 289 which operates in an inclined slot 290 in the bar 273. Normally, the arms 285 are in their forward position, as shown in Fig. 19, the pins 289 will occupy the lower ends of the slots 290, and the alining bar 272 will be elevated out of the path of the selecting bars 175, the tracks 207 at this time being forward. When, however, the links 280 are drawn rearwardly the pin 289 will occupy the upper ends of the slots 290, thereby causing lowering of the alining bar 272 into the path of the selecting bars 175, and when the dogs are tripped to release the selecting bars the latter move forward under the frictional action of the pinions 180 until they come against the bar 272, the latter serving to arrest them in their normal position.
- The bars 213, one of which is located at each side of the carriage 176, are guided at their rear ends by the stationary supports 291, a spring 292 operating upon each of these bars to move the same forwardly. The rear end of each bar 213 has a bevel 293 arranged to coöperate with a dog 294 carried by the rotating sprocket wheel 19 of the sector drum when the sectors resume their initial position, the bars 213 being deflected forwardly by the passage of the dogs 294 and then reengaging behind said dogs to prevent rebound of the sectors. Each bar 213 is provided with a pin 295 which is arranged to ride up an inclined projection 296 whereby the hook 212 on the forward end of each bar is disengaged from the lug 211 on the respective track 207, the tracks being then free to shift forwardly under the action of the links 280.
- The casting mechanism in the present instance is mounted on the frame 3 and in a position substantially diametrically opposite to the selecting mechanism. The vise 115 and mold, however, are mounted on a bracket 297 which projects rearwardly from the frame 2. The bracket 297 supports a rail 298 which extends transversely of the machine, and a pair of slides 299 and 300 are mounted to reciprocate in unison toward and from one another on said rail, the approaching and receding movements of the slides being effected by a screw 301 which embodies right and left-hand threads engaging the respective slides, the outer end of the screw shaft having a pinion 302 thereon which is connected through the train of gears 303, 304 and 305 to a pinion 306, the latter coöoperating with a gear sector 307

carried at the outer end of an arm 308. Said arm 308 is pivoted at 309 and carries a roller or projection 310 which coöperates with an operating cam 311, said cam being 5 mounted on the shaft 221 and driven by a gear 313 to which it is connected and by the coöperating gears 314 and 315, the gear 315 being fixed to an intermittently revolving shaft 316 which is driven by the 10 gears 317 and 318, the latter gear being on the main continuously revolving shaft 37, and the rotation of the shaft 316 being controlled by a clutch 319 which is operated by a clutch-shifting lever 320, the latter 15 having a pin or projection 321 which is adapted to be engaged by an inclined lug 322 on the face of the gear 313 to disengage the clutch and thereby interrupt rotation of the shaft 316 after each cycle of operations has been completed. A buffer 323 is also preferably provided to minimize jar when the gears 313 and the parts connected thereto come to a state of rest, the buffer being acted on by a cushioning spring 323^a 20 which absorbs the impact to which the buffer is subjected when the inclined lug 322 attached thereto comes against the pin 321 on the clutch-shifting lever.

The slides 299 and 300 carry a pair of 25 complementary mold sections 324 and 325, the mold section 325 having a recess 326 which, when the mold sections are brought together, will be opposite to the flat portion 324^a of the mold section 324 and will thus produce a 30 mold cavity in which the slug is cast. The slides 299 and 300 also carry a pair of vise jaws 327 and 328 which are adapted to gather together the selected matrices and to clamp them in a line of the desired length.

40 A pair of complementary alining bars 329 and 330 project from the inner sides of the vise jaws, these alining bars entering the apertures in the bodies of the selected matrices whereupon the approaching movement of 45 the vise jaws is interrupted, the matrix carrying sectors are shifted forwardly, thereby causing the selected matrices to be drawn out a suitable distance from the peripheries of the sectors, and while the latter are in 50 their forward position the approaching movements of the vise jaws are resumed, whereupon the vise jaws gather together the line of matrices into a line of the desired length, this being permitted by the flexible 55 stems supporting the matrices. The final closing movements of the vise jaws cause the alining bars 329 and 330 to produce accurate alinement of the matrices. In order to maintain the proper relation between the alining 60 bars 329 and 330, they are preferably formed on their coöperating faces with ribs 331 and 332 and corresponding grooves 333 and 334.

The mold sections 324 and 325 are movable laterally with relation to the corresponding 65 vise jaws 327 and 328. In the present in-

stance, the mold sections are supported on pins 335 and 336, and the springs 337 and 338 operate to normally force the mold sections rearwardly with relation to the vise jaws. The mold section 325 is provided with 70 an ejector for removing the slug therefrom. In the present instance, this ejector is in the form of a spring plunger 339 which extends through the top of the mold so as to operate to push the slug out of the recess 326. The 75 ejecting pin or plunger 339 is depressed at the proper time by an arm 340 which is fixed to a shaft 341, said shaft being rocked at appropriate intervals by an arm 342 fixed thereto, a link 343, an arm 344 to which said link is connected, said arm 344 being pivoted to the frame at 345, and a link 346 which carries a roller or projection 347 operating in a cam groove 348.

349 designates a galley to receive the 85 slugs after they have been cast and trimmed. The galley is provided with a reciprocating follower 350 for advancing the slugs therein and to provide room to accommodate the incoming slugs which enter the galley endwise through a slot 351 formed in the inner side wall of the galley. The follower is reciprocated by a link 352 which is attached thereto and an arm 353 which is fixed to the 90 ejector shaft 341. The slugs are trimmed by 95 passing endwise through a trimming knife 354 which, as shown, is three-sided and operates to trim the two flat sides and the foot or bottom of the slug, the trimming knife being in alinement with the slot 351 leading 100 to the galley. The slugs are successively positioned to enter the trimming knife by a slug receiver 355, and the slugs are pushed from this receiver through the trimming knife by a blade 356 which is carried by or forms a 105 part of the slide 300. The slug receiver is movable from a position to receive the slug from the mold to a position before the trimming knife. In the construction shown the 110 slug receiver is fixed to a shaft 357 and this shaft is operatively connected to the ejector shaft 341 by the gears 358 and 359. When the mold section 325 has been retracted with a slug contained in the recess 326 therein, the slug receiver 355 is swung upwardly to a 115 position beneath said mold section and the ejector then operates to remove the slug from the mold section 325, causing it to drop into the slug receiver. When the slug receiver swings downwardly into the position 120 shown in Figs. 51 and 57, the slug in the receiver is then in alinement with the trimming knife and the blade 356, and movement of the blade 356, which is carried by the slide 300, toward the trimming knife causes the 125 slug to pass through the trimming knife and the slug in advance of the one just trimmed is pushed into the galley. In order to bring the mold section 325 into a position directly above the slug receiver, a le- 130

ver 360 is provided, it being pivoted at 361 on a stationary bracket 362 and it has a hook 363 at one end to engage the rear side of the mold section 325 while its opposite end is arranged to be engaged by a projection 364 on the ejector shaft 341 so that rotation of the ejector shaft in a direction toward the ejector 340 to eject the slug from the mold section 325 will simultaneously operate the lever 360 in a direction to push the mold section 325 forwardly against the action of its spring 338, thereby bringing this mold section into a position directly above the slug receiver.

Justification of the line of matrices is effected by pushing upwardly the wedges of the spacers which have been fed into the line at appropriate intervals. The expanding or pushing upwardly of the wedges of the spacers is effected by a vertical wedge-expanding slide 365 which is mounted to reciprocate vertically in guides 366 mounted on the bracket 297, and this wedge-expanding slide is operated through a link 367 and an arm 368, the latter being fixed on a rock shaft 369. The rock shaft 369 is provided with an actuating arm 370 which is fixed thereto, and the arm 370 is connected by the link 371 to an arm 372, the latter being fulcrumed or pivoted at 373 and is provided with a roller 374 which is adapted to follow an internal cam 375 mounted on the shaft 53. The roller 374 is pressed yieldably toward its cam by a spring 377 which is connected to the rock shaft 369 through the elements 370, 371 and 372 and is of sufficient strength to force the wedges upwardly to effect justification, the cam determining the period at which justification will be effected and serving to retract the wedge-expanding slide.

378 designates a metal pot which may be of the type generally used in machines of this class, it having a spout 379 the mouth of which is adapted to engage and close the rear side of the mold, and a plunger 380 serves to eject metal from the pot through the spout and into the mold. The plunger is operated by a plunger arm 381 which is pivoted to the pot at 382, a weight 383 being mounted on the arm 381, providing the power required in actuating the plunger. The casting operation is controlled by a lever 384 which is pivoted at 385 to the base 1 and carries a roller 386 which co-operates with an appropriately shaped cam 387 whereby the weighted arm 381 and the plunger attached thereto will be permitted to drop and to force molten metal into the mold at the moment the mold sections have been closed in front of the line which is clamped between the vise jaws.

Preferably, means is provided for controlling the operation of the plunger 380 in order to prevent ejection of metal from

the pot should an incomplete line of matrices be presented at the casting point. Should the line of matrices be incomplete, then the wedge-expanding slide 365 would rise to an abnormal degree as the wedge spacers would be unable to fill up or complete the line and the forcing of metal into the mold would cause squirting of the metal between the matrices of the loose or incomplete line. In the construction shown, the shaft 382 to which the plunger actuating arm 381 is connected has a dog 388 fixed thereto and arranged to co-operate with a finger 389, the latter being pivoted to the metal pot at 390 and connected at its lower end by a link 391 to a lever arm 392, the latter being rigidly connected by the shaft 393 to a latch 394. This latch has a projection 395 which is adapted to rest upon the periphery of a sector 396, the latter being loosely mounted on the shaft 369 and is movably connected to a second sector 397 by a pin 398 on the latter which works in a slot 399 in the loose sector 396, the sector 397 being fixed on the shaft 369. The projection 395 on the latch 394 is wide enough to also rest upon the periphery of the sector 397. The sector 396 is formed with a notch 400 which is adapted to move into a position to receive the projection 395 during the normal stroke of the wedge-expanding slide 365, but should the wedge-expanding slide rise abnormally, the notch 400 will be carried past the projection 395 and the latch 394 will then be held in elevated position. While the latch 394 is in its elevated position, due to the resting of the projection 395 on the unnotched periphery of either the sector 396 or the sector 397, the finger 389 will occupy a position beneath the free end of the dog 388, and the latter will thereby lock the metal ejecting plunger 380 and thus prevent operation thereof, but when the projection 395 rests in the notch 400, the finger 389 is clear of the dog 388, as appears in Fig. 50, and the plunger 380 is then unlocked and free to operate. The latch 394 is held in co-operative relation with the sectors 396 and 397 by a spring 401.

After the mold sections have been brought together in front of the line of matrices, the metal pot is moved forwardly to bring the mouth of the spout thereof against the rear side of the mold, the cast then taking place, after which the metal pot recedes preparatory to the separation of the mold sections. To this end, the metal pot is formed with a base 402 which is slidable in a forward and rearward direction in horizontal guides 403 formed on the top of the frame 3. A cam 404 is fixed to the shaft 376 and is appropriately shaped to produce the forward and rearward movements of the metal pot, as described. An arm 405 is mounted on the shaft 373, it having a roller 406 which fol-

lows the groove of the cam 404, and the arm 405 is operatively connected to a lever 407, the upper end of the latter being connected to the metal pot.

5 The shaft 376 which carries the cams which control the justification, the movements of the metal pot toward and from the mold, the actuation of the plunger which forces the metal into the mold, and the operation of the rod 47 which controls the forward and rearward movement of the trough 16 carrying the matrix sectors is driven by 10 a sprocket wheel 408, a chain 409 coöperating therewith, a sprocket wheel 410 which drives the chain, and the gears 411 and 412, the latter gear coöperating with the gear 313.

The forward and rearward movement of 20 the trough 16 carrying the matrix sectors is effected by an arm 413 which is operatively connected to the trough at its upper end by the link 414 and is fixed to a transverse rock shaft 415, said rock shaft having an arm 416 fixed thereto and connected at its lower 25 end by a link 417 to a crank 418 at one side of the machine. The shaft 419 is rotated at appropriate intervals by the train of gears 420, 421, 422 and 423, the latter co-operating with an uninterrupted gear 424 which is carried by the gear 313.

In order to arrest the rotation of the sector-carrying drum when the latter moves in a direction to bring the selected matrices to the assembling and casting position, a 35 pair of disks 425 are fixed to the opposite ends of the drum-carrying shaft 14, each of these disks having a notch or recess 426 and is provided with a latch 427 which is pivoted to the trough at 428 and has a projection 429 40 to engage in the notch 426 when the drum has been rotated to the proper degree. The latch 427 is held in coöperative relation with the disk 425 by a spring 430. A pin 431 is also fixed to each latch 427 and this pin is 45 arranged to be engaged by an arm 432, thereby unlocking the disk 425 immediately prior to the restoring of the sectors to initial position. The arm 432 is fixed on a shaft 433, the latter being supported by a stationary bracket 434 on the stationary main frame, and a lug 435 is fixed to the shaft 433 and arranged in the path of a pin 436 on the gear 220 so that when engaged by this pin the arm 432 will coöperate with the pin 431 and thereby unlock the disk 425, the latter at this time being brought by reciproca- 50 tion of the trough carrying it into the range of movement of the arm 432.

The bar 79 which serves to reset the sector stop bars 71 is connected at each end to a link 437, each link in turn being connected to an arm 438 which is pivoted to the stationary frame 439. A link 440 is pivotally connected to each arm 438 and is provided 60 toward its rear end with a longitudinal slot

441 in which operates a pin 442, the latter being fixed to the free end of a crank 443 and said crank in turn is fixed to a shaft 444 and to an interrupted gear 445, the latter coöperating with the intermittent or in- 70 terrupted gear 446 which is fixed on the shaft 221. The forward and rearward move- 75 ment of the trough 16 carrying the sectors is preferably limited by an abutment 447 through which a pair of rods 448 pass, these rods having suitably spaced stops 449 fixed thereon to coöperate alternately with opposite sides of the abutment.

The operation of the machine as a whole is effected by the pulley 450 which is adapted 80 to be coupled and uncoupled with relation to the main drive shaft 37 by a clutch 451, this clutch being controlled by a lever 452 which latter is connected by the link 453 to a main clutch handle 454 which is located in a convenient position at one side of the key-board. The operation of the sectors, the casting mechanism and related devices which perform their cycle of operations after the selection of a line by the keyboard is controlled 85 by the clutch 319 and the manual lever 455, it being understood, however, that when said cycle of operations has been performed the clutch 319 is automatically thrown out or disengaged by the lever 320. 90

The operation of the machine may be briefly described as follows:—The selecting of the matrices to compose the line is accomplished by depressing the appropriate keys of the keyboard, the selecting bars moving 100 forwardly in succession and to different degrees corresponding to the selected matrices, and at the same time the length of the line is measured as the selecting operation proceeds. When a sufficient number of matrices 105 has been selected to complete the line, the keyboard is automatically locked. The lever or handle 455 is then operated to engage the clutch 319. This causes the slide or carriage 176 to shift to the rear, bringing 110 the rear ends of the selecting bars against the forward ends of the sector stop bars 71 and pushing these sector stop bars rearwardly different degrees corresponding to the positions occupied by the respective selecting bars, and in this way the composition 115 of the line as represented by the selecting bars is transferred to the sector stop bars. The trough 16 carrying the sectors then moves to the rear and the matrix carrying 120 sectors revolve to bring the selected matrices to the casting position, the extent of rotation of the different sectors determining the matrices that will come to rest at the casting position, and this in turn is determined by 125 the position occupied by the corresponding sector stop bar 71. The selecting bars are then restored to initial position and in readiness for the selection of a new line of matrices while the sectors are moving rear- 130

wardly and revolving. When the selected matrices have all been brought to the casting position, the drum carrying the sectors is locked by the disks 425 and the coöperating latches 427. The alining bars 329 and 330 then move together, entering the apertures in the bodies of the matrices, whereupon the trough 16 carrying the sectors shifts to the front of the machine, causing 5 the selected matrices which are impaled on the alining bars 329 and 330 to be pulled outwardly or partially withdrawn from the sectors. While the trough remains in its forward position, the vise jaws 327 and 328 come 10 together upon the ends of the line of matrices, gathering them together until the distance between the vise jaws corresponds to the length of the line. The wedge-expanding slide 365 then operates to expand the 15 spacers to justify the line, and the mold sections having also closed with the closing of the vise jaws, the cast is made by the forward shifting of the metal pot and the actuation of the metal forcing plunger therein. 20 After the cast has been made, the metal pot recedes and the mold sections and vise jaws open partially, leaving the alining bars 329 and 330 within the matrices, and while the alining bars are in this position the trough 25 carrying the sectors moves rearwardly, thereby returning the matrices to their proper positions in the respective sectors. The mold sections and vise jaws then complete their separating movement, withdrawing the 30 alining bars from the matrices and ejecting the slug just cast, and trimming the slug cast by the previous operation. The trough carrying the sectors then moves forward to its normal or initial position and at the same 35 time the sectors are revolved to return them to their normal position. After the sectors have been returned to normal position, the sector stop bars 71 are re-aligned by the operation of the resetting bar 79.

40 It is to be understood that the present invention is not limited to a construction wherein each matrix stem bears a single matrix body. Fig. 58 shows, for example, a construction wherein the matrix stem 500 carries a plurality of matrix bodies M , M' and M'' , each of these matrix bodies bearing a matrix character in a side edge thereof, and the machine may be readily arranged so that any one of these matrices as may be desired 45 can be brought into position before the mold, assuming, of course, that the mold is appropriately positioned for matrices of this kind.

I claim as my invention:—

1. In a line composing machine, keyboard mechanism comprising a set of key levers, matrix-selecting means controlled thereby, means for measuring the length of a line of matrices selected according to the varying thicknesses of the different matrices, 60 and means controlled by said measuring

means for locking the keyboard mechanism from actuation.

2. In a line composing machine, keyboard mechanism comprising a set of key levers, matrix-selecting means controlled thereby, 70 means, including a measuring device, controlled according to the varying thicknesses of the matrices for locking the key levers when a full line of matrices of different thicknesses has been selected. 75

3. In a line composing machine, adapted to assemble in lines matrices of different thicknesses, keyboard mechanism comprising a set of key levers, matrix-selecting means controlled thereby, means for measuring the length of a line of selected matrices embodying matrix-gaging devices individual to the different key levers and operative to actuate the measuring means to varying degrees according to the varying thicknesses 85 of the matrices corresponding thereto, and means controlled by said measuring means for preventing actuation of the keyboard mechanism when a full line of matrices has been selected. 90

4. In a line composing machine adapted to assemble in lines matrices of different thicknesses, the combination with matrix-selecting mechanism, of keyboard mechanism controlling the same embodying means whereby 95 each key lever is capable of selecting a plurality of matrices, means associated with the different key levers for measuring the length of a line of selected matrices according to the varying thicknesses of the different matrices selected thereby, and locking means for the keyboard mechanism operative by said measuring means. 100

5. In a line composing machine, the combination with matrix-selecting mechanism, 105 of keyboard mechanism controlling the same embodying key levers each capable of selecting a plurality of matrices, means for measuring the length of a line of selected matrices according to the varying thicknesses of the different matrices selected comprising a gage for each key lever having steps of different heights adapted to coöperate therewith, and locking means for the keyboard mechanism operative by said measuring 110 means. 115

6. In a line composing machine, the combination with matrix-selecting mechanism, of keyboard mechanism controlling the same embodying key levers each capable of selecting a plurality of matrices, and means for measuring the length of a line of selected matrices according to the varying thicknesses of the different matrices selected comprising a set of rock shafts shiftable laterally of the keyboard and carrying gages each having steps of different heights adapted to be brought into coöperative relation with the respective key levers by lateral shifting of said shafts. 120 125 130

7. In a line composing machine, the combination with matrix-selecting mechanism, of keyboard mechanism controlling the same embodying key levers each capable of selecting a plurality of matrices, means for measuring the length of a line of selected matrices according to the varying thicknesses of the different matrices selected comprising a set of rock shafts shiftable laterally of the keyboard and carrying gages each having steps of different heights adapted to be brought into coöperative relation with the respective key levers by lateral shifting of said shafts, and a line measuring member connected to said rock shafts and advanced thereby.

8. In a line composing machine, the combination with matrix-selecting mechanism, of keyboard mechanism controlling the same embodying key levers each capable of selecting a plurality of matrices, means for measuring the length of a line of selected matrices according to the varying thicknesses of the different matrices selected comprising a set of rock shafts shiftable laterally of the keyboard and carrying gages each having steps of different heights adapted to be brought into coöperative relation with the respective key levers by lateral shifting of said shafts, a line-measuring member connected to said rock shafts and advanced thereby, and a keyboard locking device controlled by said line-measuring member.

9. In a line composing machine, the combination with matrix-selecting mechanism, of keyboard mechanism controlling the same embodying key levers each capable of selecting a plurality of matrices, means for measuring the length of a line of selected matrices according to the varying thicknesses of the different matrices selected comprising a set of rock shafts shiftable laterally of the keyboard and carrying gages each having steps of different heights adapted to be brought into coöperative relation with the respective key levers by lateral shifting of said shafts, a line-measuring disk, and means operatively connecting it to said rock shafts including a multiple pawl ratchet.

10. Keyboard mechanism for machines of the class described comprising key levers, a line-measuring member, means operative by actuation of the key levers for advancing said line-measuring member different distances varying according to variations in the thicknesses of the matrices selected, and a brake for the line-measuring member having means for operating it upon actuation of each key lever.

11. In a machine of the class described, the combination with matrix-selecting means embodying a set of movable stops, of a keyboard for setting said stops for the selection of different matrices, a locking bar coöpera-

tive with said stops, and means operative according to variations in the thicknesses of the matrices selected for setting said locking bar to lock the keyboard when a full line of matrices has been selected.

12. In a machine of the class described, the combination with matrix-selecting means embodying a set of movable stops, a set of selecting bars to coöperate therewith, a traveling carriage actuated by said stops and operative to successively release the selecting bars, a locking bar arranged to coöperate with said stops, keyboard mechanism for operating the stops, line-measuring means governed according to variations in the thicknesses of the matrices selected and connected to operate said locking bar to lock the keyboard mechanism when a full line of matrices has been selected, and means on said traveling carriage for resetting said locking bar to unlocked position when said carriage is restored to initial position preparatory to the selection of the next line.

13. In a machine of the class described, the combination, of keyboard mechanism, matrix-selecting means embodying a set of selecting bars, a set of levers controlling said bars, a traveling carriage movable successively into operative relation with said controlling levers and actuated by the keyboard mechanism, and means independent of the keyboard mechanism for causing said carriage to pass one of said levers without actuating it.

14. In a machine of the class described, the combination of keyboard mechanism, matrix-selecting means embodying a set of selecting bars, a set of levers controlling said bars, a traveling carriage movable successively into operative relation with said controlling levers and actuated by the keyboard mechanism, and means independent of the keyboard mechanism for causing said carriage to pass one of said levers without actuating it during the matrix-selecting movement of the carriage and for rendering the carriage inoperative relatively to all of said levers during the return movement of the carriage.

15. In a machine of the class described, the combination of keyboard mechanism, matrix-selecting means embodying a set of selecting bars, a set of levers controlling said bars, a traveling carriage movable successively into operative relation with said controlling levers and actuated by the keyboard mechanism, and a pair of key levers carried by the carriage, one key lever rendering the carriage inoperative while passing one of said controlling levers, and the other key lever locking the carriage in inoperative relation to said controlling levers.

16. In a machine of the class described, the combination with matrix-selecting means embodying a row of controlling levers, of

5 keyboard mechanism embodying a carriage mounted to travel along said row of levers and carrying a tripping detent adapted to coöperate successively with said levers, said 5 detent being displaceable into inoperative position relatively to said levers.

17. In a machine of the class described, 10 the combination with matrix-selecting means embodying a row of controlling levers, of keyboard mechanism embodying a carriage mounted to travel along said row of levers and carrying a tripping detent adapted to coöperate successively with said levers, said 15 detent being movable vertically by the keyboard mechanism to trip said levers successively and displaceable laterally to render it inoperative relatively to said levers.

18. In a machine of the class described, 20 the combination with keyboard mechanism embodying a set of stops, of matrix-selecting means embodying a set of selecting bars to coöperate with said stops, and means operating continuously to frictionally actuate said bars.

25 19. In a machine of the class described, the combination with keyboard mechanism embodying a set of stops, of matrix-selecting means embodying a set of selecting bars to coöperate with said stops, and actuating 30 pinions coöoperative with said bars, and means operating continuously to frictionally drive said pinions to operate said bars when the latter are released.

20. In a machine of the class described, 35 matrix-selecting means embodying a set of matrix-selecting bars, a reciprocatory slide carrying said bars, a set of detents for controlling the operation of said bars, keyboard mechanism including means for individually 40 releasing said detents and positioning the selecting bars for the selection of different matrices, a restoring member for the selecting bars, and means for simultaneously releasing the detents preparatory to the restoring 45 operation.

21. In a machine of the class described, 50 the combination of a rotatable sector having circumferentially spaced matrices thereon, a toothed member rotatable with said sector, 55 the teeth of said member being located at progressively increasing distances from the center of rotation, and a stop bar adapted to be set in different positions to coöperate with different teeth on said sector and thereby arrest rotation of the sector with different matrices in operative position.

22. In a machine of the class described, 60 the combination of a rotatable sector having circumferentially spaced matrices thereon, a toothed member rotatable with said sector, 65 the teeth of said member being located at progressively increasing distances from the center of rotation, and a stop bar having a dog pivotally mounted thereon and adapted to be set at different distances from the

center of rotation of the sector to engage different teeth on said member.

23. In a machine of the class described, 70 the combination of a plurality of sectors having circumferentially spaced matrices thereon, a member rotatable with each sector and having peripheral teeth spaced at progressively increasing distances from the center of rotation of the sectors, a set of stop bars adapted to be set at different distances 75 from said center of rotation to arrest rotation of the sectors at different points, means for setting said bars according to the matrices selected, and means for resetting said bars.

24. In a machine of the class described, 80 the combination of a plurality of matrix carrying sectors, a horizontally reciprocatory carrier rotatably supporting said sectors, means coöoperative with the sectors 85 when reciprocated in one direction to select the matrices on the sectors, and alining means coöoperative with the selected matrices when the sectors are reciprocated in an opposite direction.

25. In a machine of the class described, 90 the combination with matrix-selecting mechanism and matrix alining means, of a set of matrix carrying sectors, and a reciprocatory carrier supporting the sectors and operative 95 to shift the sectors alternately into coöperative relation with the matrix-selecting mechanism and the alining means.

26. In a machine of the class described, 100 the combination with matrix-selecting mechanism and matrix alining means, of a set of matrix carrying sectors, a reciprocatory carrier supporting the sectors and operative to shift the sectors alternately into coöperative 105 relation with the matrix-selecting mechanism and the alining means, and means for rotating the sectors alternately in reverse directions.

27. In a machine of the class described, 110 the combination with matrix-selecting mechanism and matrix alining means, of a set of matrix carrying sectors, a reciprocatory carrier supporting the sectors and operative to shift the sectors alternately into coöperative 115 relation with the matrix-selecting mechanism and the alining means, means for rotating the sectors alternately in reverse directions, and a latch operative automatically to hold the sectors from rotation when in coöperative relation with the alining means. 120

28. In a machine of the class described, 125 the combination with matrix-selecting mechanism and matrix alining means, of a set of matrix carrying sectors, a reciprocatory carrier supporting the sectors and operative to shift the sectors alternately into coöperative 130 relation with the matrix-selecting mechanism and the alining means, means for rotating the sectors alternately in reverse directions, and a cushioning check operative

when the sectors are rotated to restore them to coöperative relation with the selecting mechanism.

29. In a machine of the class described, the combination of a rotatable drum having means for revolving it, a plurality of matrix carrying sectors frictionally mounted thereon and having recesses adjacent to the drum, and a spring-pressed plunger arranged to 10 coöperate with the recess of each sector.

30. In a line casting machine, a key-board selecting mechanism, actuating bars connected therewith forming matrix selecting means controlled thereby, matrices mounted

on flexible holders, sockets movably containing said holders, means for partially withdrawing the matrix holders from their sockets to bring the matrices thereon into alignment for casting a slug and mediateley connected means for restoring the matrix holders normally to their sockets without removal therefrom. 15
20

In testimony whereof I have hereunto set my hand in presence of a subscribing witness.
